CAN PUNCH
Jesse J. Morsch, 408 N. 4th St., Douglas, Wyo.
Filed Jan. 16, 1961, Ser. No. 82,959
1 Claim. (Cl. 30—6.1)

Many food containers and cans are opened by punching two holes in the top thereof, one for discharging the fluid and the other for admitting air. Such containers are used for containing beer, soft drinks, milk, lubricating oil, etc. This invention relates to a can punch for cutting and forming these two holes in the top of the container or can.

The principal object of the invention is to provide an economical, highly efficient and easily used can punch for use on a table, counter or bar and which will provide a secure support for the cans during the punching operation and which can be rapidly actuated to simultaneously form a relatively large pouring opening and a relatively small air opening in the top of cans of various sizes and types.

Another object of the invention is to provide a can punch which will move directly downwardly on the can parallel to the axis thereof so as to accurately position the holes without tilting the can and which will roll the edges of the openings downwardly and outwardly so as to avoid all sharp edges and to produce smooth rounded edges on the openings to prevent physical damage to a user when drinking directly from the can.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

FIG. 1 is a side elevational view of the improved can punch in the open or can-receiving position;

FIG. 2 is a rear elevational view thereof;

FIG. 3 is a horizontal cross section looking downwardly on the line 3—3, FIG. 1;

FIG. 4 is a front elevational view thereof;

FIG. 5 is a detail cross section taken on the line 5—5, FIG. 1;

FIG. 6 is a fragmentary detail view looking upwardly on the line 6—6, FIG. 1;

FIG. 7 is a top view of a typical can into which openings have been cut and formed by means of the improved can punch;

FIG. 8 is an enlarged fragmentary cross section through the top of the can taken on the line 8—8, FIG. 7; and

FIG. 9 is an enlarged detail view showing the appearance of the bottom of a punch element employed in the improved can punch.

The improved can punch comprises a flat, elongated rectangular base plate 10, preferably provided with cushioned foot pads 11. A frame plate 12 extends transversally of and arises vertically from the base plate 10 adjacent one extremity thereof. The frame plate 12 is braced from the adjacent extremity of the base plate by means of suitable triangular braces 13. Two arcuately notched, can-receiving angle members 14 are secured to the front of the frame plate 12 in vertically spaced relation in any suitable manner such as by means of attachment screws 15. The forward edges of the horizontal portions of the can guides 14 are provided with semi-circular notches 16 of a radius to correspond to the radius of the largest expected can.

2

Two guide track members 17 are vertically mounted on the rear of the frame plate 12 in horizontally spaced parallel relation and a cover plate 18 extends between the track members 17 and is secured thereto by means of suitable attachment screws 19 to enclose and form a vertical guide channel on the rear of the frame plate 12. A vertical slide bar 20 is slidably positioned in this vertical guide channel. The slide bar 20 has a cross-section to enable it to freely move vertically without side play or tilt. The cover plate 18 extends upwardly above the track members 17 to receive an upper spring screw 22 and the slide bar 20 is constantly urged upwardly by means of a tension spring 21 which is tensed between the upper spring screw 22 and a lower spring screw 23 which is threaded into the slide bar adjacent its lower extremity and projects rearwardly through a vertically elongated screw slot 24 in the cover plate 18.

A cap bracket 25 is formed or mounted on the upper extremity of the slide bar 20 and extends forwardly therefrom. A circular can cap member 26, provided with a downwardly extending peripheral flange 27, is fixedly mounted beneath the cap bracket 25 substantially in axial alignment with the arcuate notches 16 in the can guiding angle members 14. The cap member 26 is secured to the cap bracket 25 by means of threaded studs 28 and 29. The stud 28 extends downwardly through the cap bracket 25 and through the cap member 26 and is threaded at its lower extremity into a relatively small air hole punch 30. The stud 29 similarly extends downwardly through the bracket 25 and the cap member 26 and is threaded at its lower extremity into a relatively large discharge hole punch 31. The studs 28 and 29 are fixedly locked in position by means of suitable lock nuts 32 threaded thereon above the bracket member 25.

The slide bar 20, with its associated bracket 25 and cap member 26, can be manually forced downwardly through the medium of an actuating lever handle 33, the rear extremity of which is provided with a horizontal, tubular bearing sleeve 34 which is rotatably mounted upon a pivot bolt 35. The pivot bolt 35 is mounted in and extends between the upper extremities of two bearing brackets 36 which were mounted upon the back of the frame plate 12 by means of suitable attachment screws 37 so as to extend rearwardly and upwardly from the frame plate in parallel relation.

The lever handle 33 is supported from the cap bracket 25 through the medium of two connecting links 38 which are pivotally secured upon opposite sides of the handle 33 by means of an upper link bolt 39 and to opposite sides of the cap bracket 25 by means of a lower link bolt 40 so as to transmit movement between the handle 33 and the cap member 26.

In use, a can, such as indicated at 47, is placed on the base plate and slid rearwardly into the confines of the notches in the angle members 14. The handle 33 is then forced downwardly to cause the punches 31 and 30 to pierce and enter the can top, shown at 46, to form a pouring or discharge opening 43 and an air opening 44 successively therein, as shown in FIG. 7.

Particular attention is directed to the contour of the punches 30 and 31, more particularly punch 31. The usual can top punch simply pierces the can top and when withdrawn, pulls portions of the edges upwardly to form sharp, saw-tooth-like edges about the openings. Often the contents such as beverages, are drunk directly from the can and these sharp irregular edges often cause injury to the lips and tongue of a user. The punches in this invention are specifically designed to avoid this objection. They have a three-sided-pyramidal shape with three relatively sharp, equally-spaced inclined cutting edges 48 radiating from a common sharp center point 49. Three triangular inclined faces 50 extend between the sharp

cutting edges 48. The edges 48 cut the can top to form three triangular segments 45 and the inclined faces 50 roll these triangular segments downwardly and outwardly from the opening to form three smooth rounded sides on each opening, as shown in FIG. 8, without damaging projections.

The circular cap member 26 with its downwardly turned peripheral flange 27 serves as a deflector to prevent fluids from spouting upwardly from the occasional defective cans.

While a specific form of the improvement has been described and illustrated herein, it is to be understood that the same may be varied within the scope of the appended claim, without departing from the spirit of the invention.

Having thus described the invention what is claimed and desired to be secured by Letters Patent is:

A can punch comprising: a base plate; a frame plate extending transversely of and arising vertically from said base plate adjacent one extremity of the latter; two vertical, spaced-apart guide track members mounted on the rear of said frame plate and extending vertically therealong; a cover plate secured to and extending between said track members to enclose a vertical guide channel therebetween; a vertical slide bar slidably mounted in said guide channel and extending above said frame plate; a spring tensioned between said cover plate and said slide bar and urging the latter upwardly; a bracket member mounted on and extending forwardly from the upper extremity of said slide bar; two spaced-apart bearing brackets mounted on and extending rearwardly from said frame plate; a handle lever pivotally mounted between

said bearing brackets and extending forwardly over said slide bar; connecting links connected to and extending from opposite sides of said handle lever to opposite sides of said slide bar for transmitting vertical movement therebetween; a circular can cap member; threaded studs extending through said cap member and said bracket member and securing said cap member beneath the forward extremity of said bracket member; a downwardly-extending circular, peripheral flange surrounding said cap member; a pointed can piercing head on the lower extremity of each threaded stud; an upper can-receiving member; and a lower can-receiving member, said can-receiving members being mounted on the front face of said frame plate in vertically spaced relation and being provided with similar semi-circular sockets for positioning a can below said can cap member, so that, when said handle lever is formed downwardly, said can cap member will descend on said can to force said pointed heads through the top thereof.
